(57) **CLAIM**

The ornamental design for a vehicle, as shown and described.

DESCRIPTION

FIG. 1 is a right front perspective view of a vehicle according to the present invention.

FIG. 2 is a left rear perspective view thereof.

FIG. 3 is a front view thereof.

FIG. 4 is a rear view thereof.

FIG. 5 is left side view thereof.

FIG. 6 is a right side view thereof; and,

FIG. 7 is a top view thereof.

Any elements shown in broken lines form no part of the claimed invention, but instead show environmental aspects thereof. The broken lines adjacent to a shaded portion form an unclaimed boundary of the design.

1 Claim, 5 Drawing Sheets

FIG. 1

FIG. 2

FIG. 3

FIG. 4

FIG. 5

FIG. 6

FIG. 7
